UNITED STATES PATENT OFFICE.

JULIUS WIELAR, OF NEW YORK, N. Y.

DESIGN FOR A GAME-COUNTER.

SPECIFICATION forming part of Design No. 26,499, dated January 5, 1897.

Application filed October 1, 1896. Serial No. 607,620. Term of patent 3 years.

To all whom it may concern:

Be it known that I, JULIUS WIELAR, a citizen of the United States, residing at New York, in the county and State of New York, 5 have invented and produced a new and original Design for a Game-Counter, of which the following is a specification.

In the drawings, Figure 1 represents a face view of my game-counter. Fig. 2 is a transverse section in the plane xx , Fig. 1.

My game-counter consists of a flat oblong board A, containing nine rows of holes a b c d e f g h i . The first row a contains six holes, the second row b contains four holes, the third 15 row c contains four holes, the fourth row d contains four holes, the fifth row e contains

four holes, the sixth row f contains three holes, the seventh row g contains three holes, the eighth row h contains three holes, and the ninth row i contains three holes. 20

What I claim as new, and desire to secure by Letters Patent, is—

The design for a game-counter as shown and described.

In testimony whereof I have hereunto set 25 my hand in the presence of two subscribing witnesses.

JULIUS WIELAR.
